TABLE

William Reid Sharp, Benton, England

Application January 12, 1938, Serial No. 184,658
In Great Britain March 2, 1937

6 Claims. (Cl. 311—93)

This invention consists in an improved table.

The object of the invention is to provide an articulated table which automatically takes up a single predetermined position providing a horizontal support (hereinafter referred to as the retracted position), but which is capable of movement in one direction from its retracted position without any movement taking place between its lower portion and the ground, so that

for example when it is used as a writing or reading desk, the mere movement of drawing the top towards the user enables the said top to be brought over the user's knee so that if desired the table can be used in a reclining position, and

the user does not have to sit "at" the table but can bring the table top into any desired position to suit his convenience, the table assuming its retracted position by the user's merely pushing the top away. Another object is to provide an improved form of ironing table; and a still further object of the invention is to provide an improved form of folding dinner wagon.

The table according to the invention comprises a top pivotally connected about an axis at one end to inclined supporting means which at their lower end are pivotally connected to a base about an axis, and single stop means adapted to co-operate with said top, supporting means and base, in such a manner that in one direction the table

top may be moved until the assembly automatically takes up a substantial Z form with the support means as the inclined member while in the other direction it is freely movable without the necessity of releasing any holding means.

By "single stop means" is meant stop means which engage at one position only as distinguished from stop means which have a variety of engaging positions for example a pawl and a series of ratchet teeth."

In one form the stop means are interposed on the one hand between the table top and the supporting means and on the other hand between the supporting means and the base.

The invention will now be described by way of example with reference to the accompanying drawings.

In the said drawings:

Fig. 1 is a perspective view of one form of the invention, the table being in its retracted position or position of rest.

Fig. 2 is a perspective view of the table shown in Fig. 1 in use as a writing desk.

Fig. 3 is a perspective view showing the table of Figs. 1 and 2 folded against a wall.

Fig. 4 is a perspective view of another form of table in its rest position.

Fig. 5 is a perspective view of the table of Fig. 4 in use as a desk.

Fig. 6 is a perspective view of the table of Figs. 4 and 5 folded against a wall.

Fig. 7 is a side view showing the invention applied to an ironing table.

Fig. 8 is a plan of Fig. 7 but folded.

Fig. 9 is an elevation of Fig. 8.

Fig. 10 is a side view showing the invention applied to a dinner wagon.

Fig. 11 is a side view of the dinner wagon of Fig. 10 folded up.

Fig. 12 is an end view of Fig. 10.

Fig. 13 is a sectional elevation of a table with a reversible top.

Fig. 14 is an end view partly in section of Fig. 13.

Fig. 15 is a side elevation of a tubular form of table.

Fig. 16 is a side elevation of another form of table having two inherent stable supporting positions.

Referring more particularly to Figs. 1 to 3, the table comprises wide supports 1 to which the top 2 and base 3 are pivoted at 4 and 5 respectively so that in the one direction they may be swung between said supports to fold the table but in the other direction abut against abutments 6 on the inner faces of the supports 1, said abutments being arranged on the sides of the supports 1 remote from the pivoting axes 4 and 5. This form of table lends itself to a simple form of bracing by means of a box 7 which is arranged mid-way between the ends of the supports 1 which are thus joined together, so that said box 7 serves the double purpose of bracing the supports 1 and providing a container for papers, note-paper and so forth. To give the necessary distance between the pivoting axes and the points of support for the top and the base, the supports have laterally projecting bosses 1a and the table top and base have corresponding bosses 2a, 3a formed thereon which are pivotally mounted on the support 1a. Transverse battens 1b are provided on the outside at each end of the supports 1 for strengthening purposes.

In use, assume it is desired to use the table while the user is sitting back in an easy chair 50 or a chesterfield. The table is arranged in front of the user in its position of rest with the free end of the table top nearest the user. When the table is to be used for example as a desk or the like, all the user has to do is to pull the table top 55

- to him until its free edge rests on his lap as shown in Fig. 2. The angle of the table top may be adjusted thereafter by varying the distance along the floor between the user and the base.
- 5 When the table is done with for the time being, the user merely pushes the table top away from him until the assembly is again in the position of equilibrium, where the table top is clear of his knees.
- 10 The above construction enables the table to be folded when it is not required for any use. This is effected by swinging the top 2 and bottom frame 3 away from the abutments 6 until they have nearly swung through 360 degrees and lie 15 substantially parallel with and between the supports 1. The folded table can then be leaned against a wall as shown in Fig. 3 where it may be used as a paper holder.

In the form shown in Figs. 4 to 6, 8 indicates 20 the diagonal supports and 9, 10 the table top and the bottom frame respectively. Pawls 11 are pivotally mounted on the inside of the top 9, and pawls 12 are pivotally mounted on the inside of the lower portion of the supports 8, said 25 pawls being respectively connected by bars 13, 14. Stops 15 are provided on the supports 8 for limiting the angular movement of the pawls 12 so that when the table is unfolded the pawls 12 will drop into the correct position to abut against 30 the side members of the frame 10 which are grooved or recessed at 10a to receive projections 12a on the free ends of the pawls 12. The upper pawls 11 are extended beyond the pivoting points as at 11a so that the extensions abut against the 35 underside of the table top 9 when in the desired position. With this form by merely holding the table top 9 horizontal and allowing the support 8 and base 10 to drop the table may be assembled. This form of table is adapted for use for camping 40 owing to its relatively light construction, and also for ironing purposes where an overhanging ironing board is required.

Fig. 5 shows the table in the position it will 45 occupy when drawn towards the user similarly to the illustration in Fig. 2. Fig. 6 shows the table folded up. It will be noticed that the hinged ends of the lower frame 10 are tapered away from the hinge. This causes said frame when folded against the supports 8 to press 50 against the latter as will be seen from Fig. 6, so that the folded table may be placed vertically against the wall. This feature may be taken advantage of when using the table according to Fig. 5; for instead of leaving the frame 10 on 55 the floor it may be swung up against the supports 8 where it will remain pressed against the latter until the supports are swung into a position in which the hinge axes overhang the tapered ends of the frame 10, which will then drop 60 into the horizontal position shown in Fig. 5.

If desired short legs 16, preferably rigidly connected at their pivot ends, may be pivotally mounted on the underside of the free edge of the table top 9 so that the weight of the latter is taken off the lap and transmitted through said short legs to the chair or the like. This form of construction is particularly adapted for use as a bed-table, the table being arranged at the side of the bed with the free edge of the 65 table top parallel with the side of the bed. When the table is to be used by the occupant of the bed, the table top is pulled over sideways with the short leg abutments swung down to rest on the bed, until it is at the desired level.

75 One form of folding ironing table is shown

in Figs. 7 to 9 and comprises a top 17 of conventional ironing board form, viz., a relatively narrow board with a pointed end, said board being mounted between a pair of supports 18 which have their lower ends pivotally connected to one 5 end of a base frame 19. Distance pieces 20 are arranged between the board 17, supports 18 and base 19 to provide space for accommodating pawls 21. The free ends of the pawls 21 have pins projecting therefrom adapted to engage in recesses 18a, 19a in said supports. This form allows the table to be collapsed and folded with the three members—that is the ironing board, the support and the base—in the same plane as shown in Figs. 8 and 9.

Figs. 10 to 12 show the invention applied to a dinner wagon. According to this form the wagon is practically identical with the form of table shown in Figs. 4 to 6, the lower frame of which now comprises a tray 22, being mounted 20 on castors 23, while the diagonal supports 24 have extensions to receive a cross bar 25. A middle tray 26 may be pivoted at its mid-point along the supports 24 and connected by a pair of links 27 to the upper tray 28 on the one hand 25 and a similar pair of links 29 to the lower tray 22 on the other hand. The trays will thus always remain parallel whatever be the position of the supports 24. Fig. 11 shows the wagon folded up. To erect the wagon it is only necessary to 30 raise the handle 25. The trays rise with the supports 24 until the pawls drop into their engagement position as in the case of the table shown in Figs. 4 to 6. With this form one pair of pawls may be dispensed with. By dispensing with the 35 lower pair the folding of the wagon is simplified as the handle 25 may be supported by the one hand and the upper pawls released with the other hand. Alternatively the pawls may be arranged between the middle tray and the 40 supports only.

While the ironing table and dinner wagon above described will generally be used in the one position only, yet if desired, their tops or trays may be moved away from their retracted position 45 and brought into other temporary positions found more convenient, for example where the light is more favourable, the tops or trays being supported on a chair, table or other support.

Figs. 13 and 14 show a form of table similar 50 to that shown in Figs. 1 to 3, but with a reversible top 40. A groove is formed along the edges of the table as at 41, said grooves having pivot pins 42 projecting thereinto from the supports 1. By sliding the top 40 until the pins 42 abut against 55 the opposite ends of the top 40 the latter may be swung round and reversed, to provide a tray for example.

According to a modified form of construction, the supports are cranked at their ends in 60 opposite directions, the cranked portions being parallel with one another, while the top and base are each in the one plane; or the support frame may be in the one plane and the pivoted ends 65 of the top and base cranked, the one in the opposite direction to the other; or the one end of the support frame may be cranked and the end of the particular member adjacent its uncranked end, cranked. With any of these forms when the top and base are swung in the one direction the table is in its folded condition, while when they are swung in the opposite direction the cranked portions abut against the other members so that the table is maintained in an 70 75

unfolded condition with the top and base horizontal.

Fig. 15 shows an example of cranked support. The diagonal supports comprise tubes 43 having their ends cranked. The table top and base comprise tubular frames 44, 45 pivotally connected respectively to the ends of the members 43 by means of links 46, so that when in the opened out condition as shown in full lines the side members of the top 44 rest on the top cranked ends of the supports 43 and the lower cranked ends of the latter rest on the side members of the base frame 45. Abutments 47 on the side members of the top 44 and base 45 prevent relative lateral movement between the members 43, 44, 45.

Fig. 16 shows a form of table adapted to take up a number of positions independently of the user in addition to the predetermined horizontal position. The supports 48 are pivotally mounted on a base frame 49 the portions of whose side members adjacent the pivoting centre are raised to provide abutments 49a against which abutments 50 on said supports abut when the supports are either in the full line or dotted line position. In the full line position the table top 51 rests on an abutment 52 as in Fig. 1, but owing to the free portion overhanging the lower pivoting axis of the supports 48, pawls 53 on the supports 48 are adapted to engage recesses in the side members of the base 49 are preferably provided, although they are not absolutely necessary. The base 49 has hinged thereto a supplementary frame 54, the hinge 55 being on the underside so that the abutting ends of the frames 54 and 49 prevent any relative upward turning of either frame.

A pawl 56 is pivotally mounted on the underside of the table top 51 and has a projection 57 at its free end which in the full line or retracted position rests in the more remote of two recesses in the upper abutments 52. When the top 51 is extended as shown in dotted lines, the pawl 53 having first been raised, the pawl 56 may be dropped into engagement in the nearer recess of the abutment 52 to maintain the top 51 in the horizontal position or in recesses in an abutment 58 to maintain said top in inclined positions.

The pivot about which the supports 48 swing comprises a through bar 59 of round section rigidly mounted in the ends of said supports and passing through vertical slots in the side members of the frame 49. The object of this form of mounting is to permit of folding the frame 49 between the supports 48 when the table is not in use, the slots allowing the abutments 50 to pass over the ends of the enlarged portions 49a.

I claim:

1. An improved table comprising a top, supporting means and a base, the said top being pivotally connected about an axis at one end to

said supporting means which at its lower end is pivotally connected to the said base about an axis and single stop means adapted automatically to take up a single predetermined operative position, said stop means being adapted to co-operate with said top, supporting means, and base, in such a manner that in one direction the table top may be moved until the assembly automatically takes up a substantial Z form in side elevation with the support means as the inclined member and with the top and base as the horizontal members while in the other direction it is freely movable without the necessity of releasing any holding means.

2. An improved table comprising inclined supports, a table top pivotally connected about an axis to one end of each of said supports, a base pivotally connected to the other end of each of said supports about an axis the vertical projection of which is on the same side of the connecting axis between said top and said supports as the free end of said top, and single stops interposed on the one hand between said top and said supports and on the other hand between said supports and said base so that when the assembly is in the retracted position with said top above said base, said stops automatically come into operation at a predetermined operative position and prevent further movement of the top, towards the base, but allow movement of said top in the opposite direction.

3. A table according to claim 2 comprising relatively wide supports and abutments on the inner faces of said supports, said abutments being arranged on the sides of the supports remote from the pivoting axes, while the top and base are pivoted to said supports so that in the one direction they may be swung between said supports to fold the table but in the other direction about against said abutments.

4. A table according to claim 2 wherein the stops comprise pawls, and further stops against which said pawls are adapted to abut to ensure said pawls moving into the predetermined operative position when the table is moved into the retracted position.

5. A table according to claim 2 wherein the supports are cranked at their ends in opposite directions, the cranked portions being parallel with one another the top being adapted to be supported by the upper cranked portions of the supports and the lower cranked portions being adapted to be supported by the base when the table is in the retracted position.

6. A table according to claim 2 comprising further abutments on the base to limit the movement of the supports when in the extended position, and pawls on the underside of the table top for abutment with the supports when the table is extended.

WILLIAM REID SHARP.
